UNITED STATES PATENT OFFICE.

GUY E. BOGGS, OF KAUFMAN, TEXAS.

COTTON-PICKING MACHINE.

Application filed January 15, 1923. Serial No. 612,687.

This invention relates to a cotton picking machine, one of the objects being to provide a pneumatic cotton picker utilizing a number of gathering tubes carrying nozzles through which a suction will be set up so that when one or more of the nozzles are placed against a boll of cotton the fibres will be sucked into the machine and deposited in a suitable container provided therefor.

A further object is to provide means close to each nozzle whereby suction through the nozzle can be controlled readily by the operator.

Another object is to provide a cotton picking apparatus in the form of a complete unit adapted to be placed on a wagon body or the like and which, when operated, will quickly fill the body with the harvested cotton.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a side elevation of the cotton picking apparatus in position on a wagon body.

Figure 2 is a rear elevation of the fan casing and the manifold at the intake side thereof.

Figure 3 is a section through the manifold.

Figure 4 is an end elevation of the manifold.

Figure 5 is an elevation of one of the hose connections.

Figure 6 is a view of the connection taken at right angles to Figure 5.

Figure 7 is a side elevation of one of the nozzles.

Figure 8 is a bottom plan view of the nozzle, a portion being broken away.

Referring to the figures by characters of reference 1 designates a base on which is mounted a motor 2 preferably in the form of an explosive engine. A fan casing 3 is mounted on the base and the fan (not shown) therein is adapted to be driven from

the motor by a belt 4 or in any other suitable manner. The outlet portion 5 of the fan casing is coupled to a delivery pipe 6 which is curved downwardly and opens 60 through the base 1 so that cotton delivered from the fan casing will be directed into the wagon body 7 on which the base 1 is mounted.

Secured to the inlet portion of the fan casing 3 is an intake manifold comprising a tubular body 8 from the outer end of which are extended tubular branches 9. To each of these branches is attached a flexible tube 10 of any desired length and each tube 70 has a connecting member 11 secured to the outer end thereof. As shown in Figures 1, 5 and 6 each connecting member is preferably Y-shaped, the branches 12 thereof being connected to extension tubes 13. 75

Connected to the free end of each extension tube is a tubular nozzle 14 connected by an elbow 15 to a flared or conical head 16. Formed in the nozzle 14 near the elbow is an air inlet opening 17 and a gate valve 18 is 80 arranged within the nozzle and is adapted to close the opening. A finger piece 19 is extended outwardly from the gate valve and this valve is preferably connected to the nozzle by means of a hinge 20. 85

As heretofore pointed out one nozzle is carried by each extension tube. The base 1 is to be placed on the body of a wagon and the wagon is to be drawn along a cotton field with one operator carrying two of the 90 nozzles 14. In the apparatus illustrated five operators would be necessary, one for each pair of extension tubes. When the engine 2 is set in motion and the fan operated a suction will be set up through all of the 95 tubes and the air expelled from the fan casing will be directed into the body 7. The operators hold the nozzles 16 close to the cotton bolls to be picked and the suction will be sufficient to draw the cotton into the 100 nozzles so that it will be sucked into the casing 3 and then blown into the body 7.

Whenever it is desired to interrupt the suction through any one of the nozzles the operator merely releases the finger piece 19 105 so as to open the gate valve 18 and bring it to its normal position shown by dotted lines in Figure 8. This will allow air to enter the nozzle through opening 17 instead of head 16. 110

By providing an apparatus such as described cotton can be picked readily from

two or more rows at one time and the cotton will be promptly directed into the body 7. Thereafter the apparatus on the base 1 can be lifted off of the body, the wagon conveyed from the field and the apparatus placed on another wagon body brought to position in the field.

What is claimed is:—

10 Cotton picking apparatus including a suction tube, a nozzle carried thereby having an opening in the wall thereof, a flap valve hingedly connected to the nozzle and mov-

able to position to close the opening, said valve being normally extended into the nozzle to partly close the passage through the nozzle and a finger piece extending from the valve and outwardly from the nozzle for actuation by a finger of an operator to shift the valve away from normal position and to close the opening.

15 In testimony that I claim the foregoing as my own, I have hereto affixed my signature.

20 GUY E. BOGGS.
